CLAIM

The ornamental design for a sofa and table set as shown and described.

DESCRIPTION

FIG. 1 is a perspective view of a sofa and table set showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front, bottom, and right side perspective view thereof;

FIG. 9 is a perspective view of an arm sofa component of the sofa and table set of FIG. 1, shown separately to reveal aspects of the design that may not be apparent in other views;

FIG. 10 is a perspective view of an armless sofa component of the sofa and table set of FIG. 1, shown separately to reveal aspects of the design that may not be apparent in other views;

FIG. 11 is a perspective view of a corner sofa component of the sofa and table set of FIG. 1, shown separately to reveal aspects of the design that may not be apparent in other views;

FIG. 12 is a perspective view of a table component of the sofa and table set of FIG. 1, shown separately to reveal aspects of the design that may not be apparent in other views;

FIG. 13 is a perspective view of the sofa and table set of FIG. 1 in a second alternate configuration;

FIG. 14 is a perspective view of the sofa and table set of FIG. 1 in a third alternate configuration;

FIG. 15 is a perspective view of the sofa and table set of FIG. 1 in a fourth alternate configuration; and,

FIG. 16 is a perspective view of the sofa and table set of FIG. 1 in a fifth alternate configuration.

1 Claim, 16 Drawing Sheets
